UNITED STATES PATENT OFFICE.

JACOB F. BLINE, OF NORMAN, OHIO.

HARNESS CONNECTION FOR NECK-YOKES.

SPECIFICATION forming part of Letters Patent No. 714,184, dated November 25, 1902.

Application filed January 15, 1902. Serial No. 89,862. (No model.)

To all whom it may concern:

Be it known that I, JACOB F. BLINE, a citizen of the United States, residing at Norman, in the county of Licking and State of Ohio, 5 have invented certain new and useful Improvements in Harness Connections for Neck-Yokes, of which the following is a specification.

This invention relates to double-harness 10 and neck-yoke connections, and has special reference to a simple and effective harness connection or attachment for neck-yokes to insure an easy and permanent attachment of the neck-yoke with the harness of the 15 animals.

To this end the invention contemplates a simple and novel relation of elements coöperating with the neck-yoke and the harness and comprising means for holding the yoke 20 and choke straps of the double harness in permanent operative relation, while at the same time permitting of the connecting up of the harness with the neck-yoke or disconnection therefrom by a single operation 25 and through the medium of a single coupling element.

With these and many other objects in view, which will more readily appear as the nature of the invention is better understood, the same 30 consists in certain novel features of construction, combination, and arrangement of parts, as will be hereinafter more fully described, illustrated, and claimed.

The essential features of the invention are 35 necessarily susceptible to some structural modification without departing from the spirit or scope thereof; but a preferred embodiment of the invention is shown in the accompanying drawings, in which—

40 Figure 1 is a perspective view of an end portion of a neck-yoke and the harness elements which are designed to be coupled together through the medium of the instrumentalities contemplated by the present invention. Fig. 2 is an enlarged detailed sectional view of the fastening member which constitutes a ferrule attachment for the end of the neck-yoke. Fig. 3 is a detail perspective of the coupling member or ring carrying the 45 strap-runner, with which is connected the choke-strap of the harness.

Like reference-numerals designate corre-

sponding parts throughout the several views of the drawings.

In carrying out the invention the same is 55 preferably associated with the ordinary type of neck-yoke, (designated by the numeral 1 in the drawings,) and as no special change is made in the construction of the yoke or tree and its relation to the pole it has been deemed 60 sufficient for illustrative purposes to show an end portion thereof with which the present invention coöperates.

In adapting the invention to a neck-yoke the latter has fitted upon one end thereof a 65 fastening member 2. This fastening member is preferably in the form of a metallic ferrule or cap consisting of a tubular body closed at its outer end and tightly fitted upon the tip or end of the neck-yoke body, so as 70 to constitute a permanent part of the fitting thereof. A distinctive feature of the invention resides in providing the metallic ferrule or cap 2 at one side thereof with a longitudinally-disposed bearing-offset 3, having formed 75 therein adjoining the body portion of the ferrule or cap a bearing-eye 4. The bearing-eye 4, which is formed in the offset 3 of the ferrule or cap, is shaped to provide a well-defined bearing for loosely and freely receiving therein the coupling-ring 5, while at the same time not permitting an undue or unnecessary play thereof. To effect this result, the said bearing-eye 4 is preferably provided with oppositely-arranged grooved or concaved side 80 walls 6, forming well-defined seats or bearings in which the ring 5 may be turned, according as stress is placed thereon in an inward or outward direction, and by reason of the shape of the walls 6 the cross-sectional 85 area of the eye 4 is substantially the same shape as that of the coupling-ring 5.

The bearing-eye 4 is in communication with an entrance-opening 7, formed in the outer side of the offset 3 and permitting of the 90 ready positioning and removal of the ring. The bearing-eye is normally closed through the medium of a spring-actuated fastening-bolt 8, normally projected across the entrance-opening 7 under the influence of a 95 pressure-spring 9, seated behind the bolt 8 within the longitudinally-disposed bolt-recess 10, formed within the offset 3. The latter is further provided in the front side or wall

- thereof with a longitudinally-disposed guide-slot 11, through which projects the finger-button 12 for drawing back the bolt to uncover the opening 7 whenever this is desired.
- 5 The said bolt 8 is only sufficiently long to permit of the free compression of the spring. The coupling-ring 5 is materially larger than the end of the pole over which it is fitted, so as to freely receive therethrough the 10 yoke-strap 13 of the harness, and in addition to receiving the said yoke-strap the ring has permanently fitted thereto a strap-runner 14. This strap-runner consists of a metallic body provided at one end with a slide-eye 15, 15 loosely mounted upon the ring 5, and at its other end with a rectangular strap or billet-loop 16, through which is passed the choke-strap 14^a of the harness. The ring 5 therefore provides a direct operative connection 20 between the yoke-strap and the choke-strap, and both are properly connected with the neck-yoke by the simple act of attaching the coupling-ring in the position already indicated.
- 25 From the foregoing it is thought that the construction, use, and many advantages of the invention will be readily apparent without further description, and it is to be understood that various changes in the form, 30 proportion, and minor details of construction

may be made within the scope of the invention without departing from the spirit or sacrificing any of the advantages thereof.

Having thus described the invention, what is claimed, and desired to be secured by Letters Patent, is—

In a releasable harness connection for neck-yokes, the combination with the neck-yoke, and the yoke and choke straps of the harness, of a fastening device carried by the 40 neck-yoke at the end thereof and including a bearing, a common coupling member for the harness elements consisting of a large end ring adapted to freely take over the end of the neck-yoke and to be detachably held 45 in the bearing by said fastening device, said ring permanently receiving the yoke-strap and serving as a carrying and connecting element for both the yoke and choke straps, and a runner having a permanent slidable 50 engagement with the coupling-ring and provided with a billet-loop permanently engaged by the choke-strap.

In testimony whereof I affix my signature in presence of two witnesses.

JACOB F. BLINE.
